DRIVING MECHANISM FOR A WASHING MACHINE

John T. Hume, Chicago, Ill., assignor to Electric Household Utilities Corporation, Cicero, Ill., a corporation of Illinois

Application November 13, 1930, Serial No. 495,445

1 Claim. (Cl. 192—18)

This invention relates to improvements in washing and drying machines and its purpose is to provide an improved machine comprising means for washing the clothes and also means for drying them after they have been washed. The principal object of the invention is to provide an improved washing machine having a tub wherein the clothes are washed and comprising a clothes agitating device therein for agitating the clothes during the washing operation, in combination with a separate rotary drying basket, wherein the clothes are dried, and which is adapted to be driven at a relatively high speed so that the water is extracted from the clothes by centrifugal force. A further object of the invention is to provide an improved machine comprising a vessel adapted to contain the clothes during the washing operation and comprising an agitating device in combination with a rotary drying basket mounted above said device in said vessel and arranged to permit clothes to be inserted into and withdrawn from said vessel around its outer edge. A further object of the invention is to provide an improved means comprising a reciprocatory clothes agitating device and a rotary drying basket in combination with operating mechanism of an improved form for imparting a reciprocatory motion to the agitator and a high speed rotary motion to the clothes drying basket. Still another object is to provide a machine of the kind referred to embodying improved operating and controlling mechanism whereby the rotation of the clothes drying basket and the reciprocation of the clothes agitator may be controlled independently of each other at the will of the operator. A further object is to provide improved means for mounting the driving mechanism and the actuating motor of the machine. Other objects relate to various features of construction and arrangement which will appear more fully hereinafter.

The nature of the invention will be understood from the following specification taken with the accompanying drawings in which one embodiment is illustrated.

In the drawings,

Figure 1 shows a central vertical section through the improved washing and drying machine of the present invention;

Fig. 2 shows a detail elevation of the locking plate by which one of the operating levers of the machine is secured in a predetermined position;

Fig. 3 shows a detail vertical section, illustrat-

ing, in particular, the means for controlling the rotation of the clothes drying basket;

Fig. 4 is a detail vertical section taken on the line 14—14 of Fig. 3, and

Fig. 5 is a detail sectional view on the line 5 15—15 of Fig. 4.

As illustrated in the accompanying drawings, the supporting frame of the machine comprises a housing 20 comprising three outwardly directed arm portions 20^a to which the supporting legs 10 21 are secured or with which they are integrally formed. The legs 21 are provided at their lower ends with casters 22 adapted to revolve about vertical axes and comprising rollers which rest upon the floor or other support 23. The outer 15 ends of the arm portions 20^a of the housing are secured to a cylindrical frame member 24 which may preferably be formed of sheet metal or the like and which extends downwardly so as to partially enclose the housing 20 and parts carried 20 thereby. The housing 20 is adapted to contain the driving mechanism of the machine and the upper portion 20^b thereof is removable, upon removal of the cap screws 27, so that access may be had to the parts within the housing.

The frame structure described above is adapted to support the washing tub or vessel 30. Within the upper part of the washing tub 30, there is located the clothes drying basket 40.

A hollow vertical center post 45 projects below the bottom of the tub and extends upwardly therein to a point adjacent the bottom of the drying basket 40. The cover portion 20^b of the housing is provided with an upwardly extending central hub 46 which is closely fitted by that 35 portion of the center post 45 which extends beneath the bottom of the tub.

Around the center post 45 within the tub 30, there is located the clothes agitator 51. This agitator is adapted to revolve about the center 40 post 45 and may preferably have a reciprocatory motion in order that the clothes may be more effectively agitated within the tub. The agitator 51 is actuated by a driving tube 52 which extends upwardly within the center post 45. The 45 tube 52 is spaced from the center post at its lower end by a bushing 53, within which it revolves.

A driving shaft 61 for the basket 40 is located within the hollow driving tube 52. At its lower end, the shaft 61 is rotatably mounted within a 50 pinion 66 which has an upwardly extending hub 66^a secured to the lower end of the driving tube 52 which is driven thereby. The pinion 66 is located within the upper part of the housing 20 and the shaft 61 extends downwardly beneath this 55

pinion with its lower end journaled within a gear 67 by which the shaft is driven for the purpose of rotating the basket. The drying basket 40 is adapted to be driven at a relatively high speed through the driving shaft 61 by means of the spiral gear 67, heretofore referred to, which is actuated directly by the spiral pinion 81. This spiral pinion is provided with a depending hub 67^a which is journaled in a bearing 105 formed in the lower wall of the casing 20. A washer 106 is interposed between the bearing 105 and the lower face of the gear to receive the downward thrust transmitted to the gear and the gear is centrally apertured to receive the lower end of the shaft 61 which is journaled therein. In order to provide a driving connection between the gear 67 and the shaft 61, when desired, a horizontal friction disc 107 is fixed on the shaft 61 immediately above the gear. The lower face of this disc is adapted to contact, when the shaft 61 is in its lowermost position, with a plurality of friction blocks 108, formed of cork or the like, which are secured in recesses 109 formed in the upper face of the gear. Small apertures 110 communicate with these recesses from the under side of the gear to facilitate the removal of the blocks when desired. The friction blocks project above the upper face of the gear and contact with the lower face of the disc so that a driving connection is thereby established to cause the basket 40 to be rotated at a sufficiently high speed to effect the removal of the moisture from the clothes by centrifugal force.

In order to disconnect the driving gear 67 and the disc 107 to arrest the rotation of the basket, means are provided for elevating the disk 107, along with the shaft 61 and the basket, by means applied to the lower end of the shaft. This elevating means, shown particularly in Figs. 1, 3 and 4, comprises an actuating lever 115 which projects through an opening in the one side of the circular frame member 24 and which extends above the housing 20 with its inner ends pivoted at 116 upon a bracket 117 which is formed integrally with the housing. At a point adjacent the bracket 117, the lever 115 bears upon a cap 118 which is mounted upon the upper end of a pin 119. A coil spring 120 is interposed between the cap 118 and the boss 121 which is formed on the housing so that the pin 119 tends normally to resume its uppermost position. The pin 119 extends downwardly through the housing, as shown in Fig. 13, with its lower rounded end seated within a recess 122^a which is formed in one end of a lever 122. This lever is pivoted on a pin 123 which extends between a pair of ears 124 projecting upwardly from the bottom of the housing, and the end of the lever opposite the pin 119 is provided with another recess 122^b in which

there is mounted a spherical ball 125. This ball contacts directly with the lower end of the shaft 61 so that when the lever 122 is rocked about its pivot by the depression of the pin 119, the shaft 61 and disc 107 are elevated, thereby moving the disc 107 out of engagement with the friction blocks 108 which are carried by the gear 67. The driving connection to the shaft 61 is thus broken and, in order to hold the shaft and the connected basket 40 stationary during this time, the housing 20 is provided with a transversely extending bar 126, provided with recesses 126^a in which there are mounted friction blocks 127, of cork or the like, having their lower parts projecting below the bar so that they are adapted to engage the upper side of the disc 107 when the disc and shaft 61 are elevated. The disc is then held against rotation so that the basket 40 is prevented from rotating during the time that the drying operation is not being carried on. In order that the disc 107 may be held in the elevated position which has just been described, the annular frame member 24 of the machine is provided adjacent the actuating lever 115 with a plate 130 having a slot 130^a through which the outer portion of the lever extends, as shown in Fig. 3. One side of this slot is provided with a notch 131 having an overhanging tooth 132 on the side thereof so that when the lever 115 has been depressed, it may be moved laterally and caused to engage the notch 131 so that it is thereby held in that position corresponding to the position wherein the disc 107 engages the stationary friction block 127.

The driving mechanism for imparting an oscillatory motion to the clothes agitator, is described and claimed in my copending application Serial No. 338,456, filed February 8, 1929.

Although one form of the invention has been shown and described by way of illustration, it will be understood that it may be constructed in various other embodiments within the scope of the appended claim.

I claim:

The combination in driving mechanism for a washing machine, of a frame adapted for supporting a tub, a housing carried by said frame, a gear journaled in said housing, a vertical shaft having said gear rotatably mounted thereon, a friction disk secured on said shaft, a friction block mounted on said gear and adapted to engage said disk, a lever pivotally mounted in said housing and carrying a part engaging the lower end of said shaft, a pin slidably mounted in said housing and engaging said lever, and an operating lever engaging said pin and extending to the side of said frame to permit the operator to actuate said first named lever to reciprocate said shaft.

JOHN T. HUME.
